UNITED STATES PATENT OFFICE.

EDMOND E. FOURNIER AND MERTON I. VESTAL, OF FALL RIVER, MASSACHUSETTS.

TIMER.

Application filed March 28, 1921. Serial No. 456,153.

To all whom it may concern:

Be it known that EDMOND E. FOURNIER and MERTON I. VESTAL, citizens of the United States, residing at Fall River, county 5 of Bristol, Commonwealth of Massachusetts, have invented certain new and useful Improvements in Timers, of which the following is a specification.

This invention relates to timers for internal combustion engines, and consists in the novel construction, combination and relation of parts disclosed in the accompanying specification and drawings and particularly pointed out in the appended claims.

For purposes of disclosure we show an embodiment of our invention which has been found satisfactory in use and well adapted to requirements of manufacture. Throughout the specification and drawings 20 like reference characters are correspondingly applied, and in the drawings:

Fig. I is a longitudinal section through a timer in accordance with our invention.

Fig. II is a fragmentary detail in section.

Fig. III is a rear elevation of the timer casing with wire cover removed.

Fig. IV is a section along the line IV—IV of Fig. III.

Fig. V is an enlarged section diagrammatically illustrating the make and break action and

Fig. VI is a detail view of the contact carrier removed.

We have indicated at 1 the timer casing, at 2 the cam shaft, and at C the gear cover of the engine. The casing 1 is mounted upon the gear cover to turn through a portion of a revolution relative thereto when 35 the spark is advanced or retarded, and has an arm 12 operating between stop pins 12¹ and 12² by means of which it may be turned. See Fig. III.

Fast on the shaft 2 within the casing is 45 a rotor holder 3. As here shown, the holder 3 is a sleeve fitted about the inner reduced end of the shaft 2 and adjustably fastened thereto by a pin 40, see Fig. I, disposed in an arcual slot 41 cut in said reduced end of the shaft 2 and held in said slot by a clamping washer 42 and set nut 43 screwed on the threaded inner end of the shaft 2. Said sleeve 3 has an arm providing an offset socket portion 3¹ disposed parallel to the axis of rotation. The socket 3¹ has a longitudinally disposed key way 3² within which

is lodged a key 3³, see Fig. 1, formed integrally on the make and break element 4 for holding said member 4 against rotation in the socket 3¹.

Such member 4, as here shown, is a substantially cylindrical brush socketed at its outer end to receive a coil spring 5. The opposite end of said member 4 is rounded, the axis of curvature being perpendicular to 65 but offset from the axis of rotation of the shaft 2. At said end the brush 4 is centrally provided with an inserted wear piece or contact surface 4¹ of a material harder than the body of said brush. See Fig. IV. 70 Preferably the body of the brush is made of steel and the insert 4¹ is of tungsten and is fixed as by welding in an axial slot cut across the transversely curved inner end of the steel body. The key and keyway connection at 3², 3³ insures that the brush will be positioned in proper relation to the contacts 6. The free end of the coil spring 5 abuts an oil guard or shield 16 interposed 75 between the holder 3 and a shoulder 2¹ 80 formed on the shaft 2. The shield 16 prevents oil from working along the cam shaft 2 into the timer casing 1 and thence onto the contacts 6, and preferably has its rim inwardly bent as indicated at 16¹ at an angle 85 of about 15° so that any oil collecting upon the shield will flow towards the axis of rotation when the cam shaft 2 is at rest and will not pass inwardly towards the make and break member 4 and contacts 6. When the 90 cam shaft 2 is revolving, the oil is thrown outwardly away from the oil shield by centrifugal force, since the oil shield 16 is clamped to said shaft against the shoulder 2¹ thereof by the brush holder 3 and hence 95 rotates therewith. Lodged on the shaft 2 between the shield 16 and the gear cover C is an absorbent washer 23, the inner face of the gear cover having an annular shoulder 23¹ within which said washer is seated.

At the opposite end of the casing 1 is a wire cover 10. The opposing surfaces of said casing and cover are oppositely beveled as indicated at 22 to provide an oil tight seat for the annular reduced rim 21 of the 105 contact-carrying disc 7. The disc 7 is preferably constructed throughout of some appropriate insulating material, as fibre, and is provided at symmetrically spaced points with a series of contact members 6 corresponding in number to the number of engine cylinders.

In order to properly locate the contact disc 7 within the casing 1, said casing is slotted from one end towards the other end, as indicated at 19, and the disc 7 is provided with a key portion 20 adapted to lie within the keyway thus provided in the casing. See Fig. II. In addition to its function as a keyway, the slit 19 also serves as a drain for any oil which may drip from the oil shield 16. Moreover due to the inherent resiliency of the metallic casing, said slit tends to close, thereby causing the disc 7 to be tightly clamped.

The disc 7 has an enlarged axial opening 25 therethrough within which the inner end of the cam shaft 2 extends. The opening 25 is larger than the set nut 43 on the cam shaft 2 and accordingly not only permits access to said nut but in itself constitutes a sight opening through which the wiring to the contacts 6 may be viewed without dismantling the entire timer. Inasmuch as entrance of oil into the timer casing is prevented by the oil shield 16 and oil tight joint at 22 the axial inspection opening 25 may be safely made in the disc 7 without danger of oil accumulating upon the contact surfaces 6.

The contacts 6 are simple inserts of steel 30 or other suitable conducting material set through the disc 7 and having their exposed surfaces all disposed in the same plane. Each contact 6 is mounted on a binding post 61 with which connect the lead wires 8 to the coil units and spark plugs of the engine cylinders. Preferably the inner face of the disc 7 is radially slotted as indicated at 7¹, Fig. VI, to receive the inserts 6.

The inserts 6 are thus relieved at their 40 sides, by said slots 7¹, so that the brush 4 is wholly supported on the metallic contacts as it rides onto a contact. This action is illustrated diagrammatically in Fig. V wherein the contact point 4¹ of the brush 4 is shown as riding upon one of the inserted contacts 6, along a single line of contact only and said line of contact is parallel with the front edge of the insert. This insures a clean and positive contact. The make and break action therefore is not only a clean one but is a full one, since the brush comes fully onto each contact surface 6 on a single line of contact as distinguished from a line of contact which is partially on the insert 6 and partially on the fibre of the disc 7. This is due to the fact that although the brush as a whole is radial to the axis of rotation of the shaft 2, the axis of curvature at the contact end of the brush is perpendicular to but offset from said axis of rotation, see Fig. V, wherein the offset relation is visually indicated by the broken lines A, B and C in the several successive phases of travel of the brush about the shaft 2. From this figure 60 it will be apparent that the contact point 4¹

maintains constantly its offset relation throughout the entire revolution of the shaft 2 so as to come upon a contact 6 along a single line of bearing only, which line is parallel with the front edge of the insert (position B in Fig. V) and to leave said contact along a line which is at an acute angle to the rear edge of said contact (position C of Fig. V).

The cap 10 is relatively stationary mounted as to the casing by a spring 13 which is secured at one end upon the gear cover so that said cover 10 is held stationary during the rotation of the shell 1 by its arm 12 to advance or retard the spark. To this end the cover 10 has an integral lug 14 on its outer face with which engages the free end of the spring retaining arm 13. The free end of said arm 13 is forked as indicated at 13¹, see Fig. I, to fit over the lug 14. The fork 13¹ allows the arm 13 to find its own center.

The loom L for the lead wires 8 enters the cap 10 from below and has an outlet opening 11 for the wires 8 disposed in substantially the longitudinal axis of the timer. The wires 8 therefore lead into the timer shell axially and by this construction are protected against the excessive twist which results with lead wires which enter the shell peripherally when the timer shell is turned to advance or retard the spark. The loom is held within the cap 10 with its outlet opening 11 disposed in the axis of the timer shell by a rivet 15, see Fig. I, which extends through the loom and cap, and has its outer end clinched over the lug 14 on said cap. Said loom is also utilized as a conductor for the lighting wires 17 to the headlights of the machine.

It will be noted that the brush 4 is deeply recessed to receive the major portion of the spring 5 and that the outer end of the spring is bent outwardly as indicated at 5¹ to form a lock between the brush holder 3¹ and the oil shield 16.

It will also be noted that the brush 4 on leaving an insert 6 (see Fig. V) is supported by the fibre of the disc 7, and being offset, leaves the insert gradually, thereby reducing the burning effect as the circuit is broken.

What we therefore claim and desire to secure by Letters Patent is:

1. A timer comprising a relatively rotatable casing and a relatively stationary wire cover, a contact carrier clamped between said casing and cover, a rotor in said casing, a lug externally of said wire cover, and an arm fixed at one end and slotted at its free end to engage and automatically center itself upon said lug and holding said wire cover against movement upon rotation of the casing.
12. A timer comprising a relatively ro-

- tatable casing and a relatively stationary wire cover, a contact carrier having a reduced annular rim clamped between the opposing edges of said casing and cover, a rotor 5 in said casing, a lug externally of said wire cover, and an arm fixed at one end and forked at its free end to engage and automatically center itself upon said lug and holding said wire cover against movement upon 10 rotation of the casing.
3. A timer comprising a relatively rotatable casing having a longitudinally extending slit, a relatively stationary wire cover, a contact carrier having a reduced annular rim clamped between the opposing edges of said casing and cover, and having a key portion disposed in said slit of the casing, a rotor in said casing, and means for holding said cover against movement upon 15 rotation of said casing.
4. In a timer, oppositely disposed casing and cover members, one of said members having a longitudinally extending slit, and a contact carrier having a key portion disposed in said slit.
5. In a timer, oppositely disposed casing and cover members, one of said members having a longitudinally extending slit, and a contact carrier having a key portion disposed in said slit and having a reduced annular portion clamped between the opposing edges of said casing and cover members.
6. In a timer, oppositely disposed casing and cover members, one of said members having a longitudinally extending slit, and a disc mounted within said members and having an axial inspection opening, a plurality of spaced contact elements on said disc about said opening, an annular mounting rim on said disc clamped between the opposing edges of said casing and cover members and a longitudinally disposed key portion disposed in said slit.
7. In a timer, a plurality of spaced stationary contacts, and a rotatable brush having a curved contact end, the axis of curvature being perpendicular to but offset from the axis of rotation of the brush so that said contact end will come upon each stationary contact along a single line of bearing.
8. In a timer, a plurality of spaced stationary contacts, and a rotatable brush having a curved contact end, the axis of curvature being perpendicular to but offset from the axis of rotation of the brush so that said contact end will come upon each stationary contact along a single line of bearing which is substantially parallel to the near edge of said contact.
9. In a timer, a plurality of spaced sta-
- tionary contacts, and a rotatable brush having a curved contact end and having an axial bearing surface inserted into said end and of a material harder than the body of the brush proper, the axis of curvature being perpendicular to but offset from the axis of rotation of the brush so that said insert will come upon each stationary contact along a single line of bearing.
10. In a timer, a plurality of spaced stationary contacts, and a rotatable brush having a curved contact end, and having an axial bearing surface inserted into said end and of a material harder than the body of the brush proper, the axis of curvature being perpendicular to but offset from the axis of rotation of the brush so that said insert will come upon each stationary contact along a single line of bearing which is substantially parallel to the near edge of said contact.
11. In a timer, a rotatable brush comprising a body portion having a curved contact end, the axis of curvature being perpendicular to but offset from the axis of rotation of the brush.
12. In a timer, a rotatable brush comprising a body portion having a curved contact end, and a bearing surface of a material harder than said body portion inserted axially into said contact end, the axis of curvature being perpendicular to but offset from the axis of rotation of the brush.
13. In a timer, an insulated contact carrier having a plurality of spaced stationary contacts, and a rotatable brush having a curved contact end, the axis of curvature being perpendicular to but offset from the axis of rotation of the brush so that said contact end will come upon each stationary contact along a single line of bearing which is substantially parallel to the near edge of said contact, and will leave the opposite edge of each contact at an acute angle thereto, said contact end finding immediate support on the contact carrier as it passes off each contact.
14. In a timer, an insulated contact carrier having a plurality of spaced stationary contacts, and a rotatable brush having a curved contact end, the axis of curvature being perpendicular to but offset from the axis of rotation of the brush so that said contact end will leave each stationary contact at an acute angle thereto and will find immediate support on the contact carrier.
- In testimony whereof we affix our signatures.

EDMOND E. FOURNIER.
